UNITED STATES PATENT OFFICE.

JACOB EDWARD COFFEY, OF CASEY, ILLINOIS, ASSIGNOR OF ONE-HALF TO L. H. JOHNSON, OF CASEY, ILLINOIS.

LIQUID-DISPENSING APPARATUS.

1,180,242.

Specification of Letters Patent. Patented Apr. 18, 1916.

Application filed October 6, 1915. Serial No. 54,393.

To all whom it may concern:

Be it known that I, JACOB E. COFFEY, a citizen of the United States, residing at Casey, in the county of Clark and State of Illinois, have invented certain new and useful Improvements in Liquid-Dispensing Apparatus; and I do hereby declare the following to be a full, clear, and exact description of the invention, such as will enable others, skilled in the art to which it appertains to make and use the same, reference being had to the accompanying drawings, and to the letters and figures of reference marked thereon, which form a part of this specification.

This invention relates to new and useful improvements in apparatus for dispensing gasolene, coal oil and other liquids and consists in the provision of a simple and efficient apparatus of this nature having various details of construction, combinations and arrangements of parts which will be hereinafter fully described, shown in the accompanying drawings and then specifically defined in the appended claims.

My invention is illustrated in the accompanying drawings, in which:

Figure 1 is a central vertical sectional view showing parts of the apparatus in elevation. Fig. 2 is an enlarged detail view in elevation showing parts in different operative positions from that disclosed in Fig. 1. Fig. 3 is an enlarged detail in elevation of the mechanism in the lower part of the apparatus, and Fig. 4 is a sectional view on line 4—4 of Fig. 2.

Reference now being had to the details of the drawings by numeral, 1 designates a casing mounted upon a standard 2 and within which casing the operative parts of the apparatus are positioned. A frame 3 is mounted within the receptacle and 4 designates an exit pipe through which the liquid is dispensed and from which a vent pipe 5 rises vertically within the tank, and 6 designates an inlet pipe. A valve 7 is mounted upon a stem 8 and is adapted to regulate the inlet end of the pipe 4, said stem having a vertical play in the hollow bosses 9 which project from the standard 10. An angle lever 11 is pivotally mounted upon a pin 12

carried by the standard and has a slot 13 through which a pin 14 carried by the stem 8 passes. A spring 15 is fastened at one end in an aperture 16 of the lever 11 and its other end to an apertured lug 17 upon the frame 3. A coin chute 18 registers with a slot 19 in the wall of the casing, as shown in Fig. 2 of the drawings, and the lower portion of the slot extends laterally and has an exit opening 20 through which the coins, designated by numeral 21, are adapted to fall into a coin receptacle 22. Two parallel pull bars, designated respectively by numerals 23 and shown in section in Fig. 4 of the drawings, and having a handle 23' pivotally connected thereto, are held spaced apart by a crosspiece 24 and a spring 25 is fastened at 26 to the frame 3 and its other end to the bars 23, normally holding the same in the position shown in Fig. 2. Said bars have a longitudinal movement in slots 27 formed in the walls of the casing of the coin slot and also through the frame 3 and the casing 1.

A boxing 28, shown in edge view in Fig. 4, has flanges 29 projecting from the upper and lower edges thereof and which are guided in slots in the walls of the slotted casing, and pins 30 project from said boxing and which are engaged by forked arms 31 of the members 32, which is pivoted upon a pin 33, carried by the angle lever 11. Said member 32, it will be noted, has a recess 34 formed in its lower end, one side of which is open and affording means whereby the tilting movement of the member in one direction may be limited. A spring 35 is fastened to the member 32 and also to the stationary float stem 36 and is provided for the purpose of giving the member 32 a swinging movement independent of the lever 11 for the purpose of kicking the coin as the member swings in one direction, causing the coin to fall into the receptacle beneath.

A float 37 is mounted upon the stem 36 and is provided with anti-friction rollers 38 upon its top and bottom which bear against the stem at points diametrically opposite, and 39 is a bracket member secured to the top of the float. An angle lever 40 is pivotally mounted upon a pin 41 carried by the standard 10 and has a short arm 42 which is

pivoted to the link 43, which latter in turn is pivoted at 44 to the lever 11, thus forming a toggle joint connection. A spring 45 is fastened at one end to the link 43 and its 5 other end to the lever 11 and serves to cause the toggle joint to straighten or buckle when the angle lever 11 is tilted to the right to cause the valve 7 to open to allow the liquid to dispense, the buckling of the toggle joint 10 serving to hold the valve open through the connections described. An adjusting screw 46 is mounted in a bracket arm 47 upon the standard and serves to adjust the swinging movement of the toggle joint in one direction. The long arm 48 of the lever 40 is positioned in the downward path of the 15 float 37.

A valve 49, regulating the inlet valve 6, is mounted in a hollow boss 51 projecting from 20 the standard 52, and 53 designates a lever with a slot 54 therein which receives a pin 55 carried by the stem 50. Said lever 53 has a downwardly projecting arm 56 which is pivoted to a link 57 and which in turn is 25 pivoted to the lower end of the lever 58 pivotally mounted upon a pin 59 carried at the end of the lever 11. A spring 60 is fastened at one end to a lateral projection of the standard 52 and its other end bears 30 against the lever 53 to the right of the standard 52. A lever 61 is pivotally mounted upon a pin 62 at the top of the standard 52 and has a rod 63 fastened to one arm which 35 rod extends vertically through the frame 3 and carries a flanged disk 64 thereon, held upon the rod by means of a set screw 65. A collar 66 is also fastened by a set screw 67 to the rod 63 and limits its downward movement. A link 68 is pivotally connected to 40 one arm of the lever 61 and its other end to a link 69 which in turn is pivoted to the upper end of the lever 58. A spring 70 is fastened at one end to the pivotal connections between the link 69 and lever 58 and its 45 other end to the boss 9. An adjusting screw 71 is mounted in the downwardly extending arm of the lever 53 and tends to adjust the swinging movements of the link 57 and lever 58 in one direction, forming a toggle joint 50 connection.

A longitudinally movable bar 72 is mounted in apertures in said frame and a bracket arm 73 and is movable between the antifriction rollers 74 upon said bracket 73, 55 and an arm 72^a has a collar 72^a thereon mounted upon the bar 72 and is held in adjusted position thereon through the medium of the set screw 72'. Said arm 72 has a forked end positioned in the path of the 60 bracket member 39 upon the float 37. The upper portion of the bar 72 is curved as at 74, forming a cam edge which causes a lateral swinging movement to be imparted to the bar 72 as the curved portion passes by the

edge of the slot 80 through which the bar 72 65 passes. A pawl 81 is pivoted to the upper end of the bar 72 and its movement in one direction is limited by a pin 81^x, said pawl being adapted to engage the flanged disk 64 as the bar 72 is moved upward, carrying 70 with it the disk and the bar 63.

Antifriction rollers 81 are mounted above and below the slot in the top of the frame through which the bar 72 passes and are adapted to bear against the opposite sides of 75 said bar 72. A bar 82 is pivotally mounted upon a pin 83 upon a lug 84 of the frame 3 and is pivotally connected at its other end to a coin slot-closing slide 85 adapted to normally hold the coin slot closed until the supply of gasoline within the tank or receptacle 80 is replenished. A rod 86 is pivotally connected at 87 to the bar 82 and has an elongated loop 88, shown in Fig. 1 of the drawings, and 89 is a finger engaging said 85 loop 88 and projects from a collar 90 which is held in adjusted position upon the bar 72 by means of an adjusting screw 91. A bracket 92 is fastened to the casing 1 and is in the path of the bar 82 and is adapted to 90 limit its upper movement.

The operation of my invention will be readily understood and is as follows: Assuming that the tank has a supply of liquid 95 therein to be dispensed, the operator drops a coin in the slot and said coin runs down the inclined chute and rests upon the horizontally disposed ledge 18^x and is positioned intermediate the bars 23 and between the crosspiece 24 and the boxing 28. The pull 100 bars 23 are then drawn out against the tension of the spring 25, causing the lever 11 to tilt and also the pivotal member 32 which is spring-pressed and which is pivoted to the lever 11. As the lever 11 tilts, the exit 105 valve 7, through its connection with said lever 11, will be raised from its seat and allow the liquid to dispense through the pipe 4. As the lever 11 tilts, the toggle link 110 connections, consisting of the lever 40 and link 43, will assume the position shown in Fig. 3 of the drawings and be held in such position by the spring 45 which will hold the lever 11 at its farthest throw to the right and the valve 7 from its seat. As the lever 115 tilts upon its pivot 12, it will be noted that the lever 58 carried by its short arm will be elevated and the link 57 will also be elevated and the spring 70 will cause the toggle link connection between the levers 11 and 53 120 to assume the position shown in Fig. 3 of the drawings. As the lever 58 and link 57 are swinging from the position shown in Fig. 1 to the positions which they assume in Fig. 3, the rod 69, which connects the upper 125 end of the lever 57 with the link 68, will cause the latter to swing against the lug 68^x but without tilting the lever 61 in its move-

ment. As the liquid is dispensed, the float 37 lowers upon the surface of the liquid and, when it comes in contact with the long arm 48 of the lever 40 and bears upon the same 5 with sufficient pressure to overcome the tension of the spring 45, the toggle joint connection between the levers 40 and 11 will assume the positions shown in Fig. 1 of the drawings, and the exit valve will close and 10 the inlet valve 49 will unseat, allowing the tank to be replenished with the liquid through the pipe 6. It will be noted that, immediately before the inlet valve is raised from its seat, the toggle joint between the 15 lever 58 and link 57, assuming the positions shown in Fig. 3, will cause a rigid connection between the levers 11 and 53. The inlet valve is normally held open by the spring 15 and the connections intermediate the 20 same and the lever 53. As the float rises with the liquid in the tank as it is being refilled and when it comes in contact with the arm 72^x, it will cause the latter and the bar 72 to be raised and the pawl 81', en- 25 gaging the flanged disk 64, will impart an upward longitudinal movement to the bar 63, tilting the lever 61, and the toggle joint intermediate the levers 11 and 53 will break and the inlet valve will seat through the in- 30 fluence of the spring 60. As the curved edge 74 of the bar 63 comes in contact with the antifriction rollers 81, a lateral swinging movement will be imparted to the bar 72, sufficient to cause the pawl 81' to swing 35 free of the disk 64 and, when the finger 89 comes in contact with the upper end of the loop 88, an upward movement will be im- 40 parted to the rod 86 and causing the bar 82 to swing up and with it the slide which covers the coin slot, thus opening the latter to allow another coin to be deposited in the aperture.

It will be noted that, after the pull bars 23 have been drawn to their outer limits and 45 released, the spring 35 connected to the member 32 will cause the same to swing upon its pivot and kick the coin out from between the two bars.

From the foregoing, it will be noted that 50 the operation of my improved liquid dispensing apparatus is automatic in its action, the valves being operated in the manner shown for filling and allowing the tank to be dispensed and, by adjusting the member 55 72^x upon the bar 72, the apparatus may be adapted to operate with different quantities of liquid contained within the tank.

What I claim to be new is:—

1. A liquid dispensing apparatus comprising a tank with an inlet and an outlet opening, valves regulating said openings, a pivotal, spring-pressed lever and means for tilting the lever in one direction, a float, float-operated toggle link connections with the

lever for causing the exit valve to close, a 65 spring connecting the float operating member and lever, and float-actuated means for causing the inlet opening to seat independent of the other valve.

2. A liquid dispensing apparatus comprising 70 a tank with an inlet and an outlet opening, valves regulating said opening, a pivotal, spring-pressed lever to tilt the lever in one direction, a float, a float-actuated member and toggle link connections between 75 the same and lever, a spring-pressed lever connected to the stem of the inlet valve, toggle link connections between said levers, and float-actuated means for breaking the toggle link connections between the levers 80 to allow the inlet valve to seat independent of the other valve.

3. A liquid dispensing apparatus comprising 85 a tank with an inlet and an outlet opening, valves regulating said opening, a pivotal, spring-pressed lever to tilt the lever in one direction, a float, a float-actuated member and toggle link connections between the same and lever, a spring-pressed lever connected to the stem of the inlet valve, toggle 90 link connections between said levers, a longitudinally movable bar and pivotal lever and link connections therewith adapted to break said toggle connection between the valve-actuating levers, and a longitudinally movable float-actuated member adapted to im- 95 part a longitudinal movement to said bar.

4. A liquid dispensing apparatus comprising 100 a tank with an inlet and an outlet opening, valves regulating said opening, a pivotal, spring-pressed lever to tilt the lever in one direction, a float, a float-actuated member and toggle link connections between same and lever, a spring-pressed lever connected to the stem of the inlet valve, toggle 105 link connections between said levers, a longitudinally movable bar and pivotal lever and link connections therewith adapted to break said toggle connections between the valve-actuating levers, a longitudinally movable 110 member, a projection therefor adapted to be disposed in the path of a float, and a pawl upon said member adapted to actuate said bar longitudinally.

5. A liquid dispensing apparatus comprising 115 a tank with an inlet and an outlet opening, valves regulating said opening, a pivotal, spring-pressed lever to tilt the lever in one direction, a float, a float-actuated member and toggle link connections between 120 the same and lever, a spring-pressed lever connected to the stem of the inlet valve, toggle link connections between said levers, a longitudinally movable bar and pivotal lever and link connections therewith adapted to break said toggle connections between the valve-actuating levers, a longitudinally movable 125 member, a projection therefor

- adapted to be disposed in the path of a float, a pawl upon said member adapted to actuate said bar longitudinally, and means for moving said member to release the pawl 5 from engagement with said bar.
6. A liquid dispensing apparatus comprising a tank with an inlet and an outlet opening, valves regulating said opening, a pivotal, spring-pressed lever to tilt the lever 10 in one direction, a float, a float-actuated member and toggle link connections between the same and lever, a spring-pressed lever connected to the stem of the inlet valve, toggle link connections between said levers, 15 a longitudinally movable bar and pivotal lever and link connections therewith adapted to break said toggle connections between the valve-actuating levers, a longitudinally movable member, a projection therefor 20 adapted to be disposed in the path of a float, a pawl upon said member adapted to actuate said bar longitudinally, disks upon said bar adapted to be engaged by said pawl, and means for tilting said member to release the pawl as the float approaches its 25 highest limit.
7. A liquid dispensing apparatus comprising a tank with an inlet and an outlet opening, valves regulating said openings, a pivotal spring-pressed lever to tilt the lever 30 in one direction, a float, a float-actuated member and toggle link connections between the same and lever, a spring-pressed lever connected to the stem of the inlet valve, 35 toggle link connections between said levers, a longitudinally movable bar and pivotal lever and link connections therewith adapted to break said toggle connections between the valve-actuating levers, a longitudinally 40 movable member, a projection therefor adapted to be disposed in the path of a float, a pawl upon said member adapted to actuate said bar longitudinally, disks upon 45 said bar adapted to be engaged by said pawl, means for tilting said member to release the pawl as the float approaches its highest limit.
8. A liquid dispensing apparatus comprising a tank with an inlet and an outlet opening, valves regulating said openings, a pivotal spring-pressed lever to tilt the lever 50 in one direction, a float, a float-actuated member and toggle link connections between the same and lever, a spring-pressed lever 55 connected to the stem of the inlet valve, toggle link connections between said levers, a longitudinally movable bar and pivotal lever and link connections therewith adapted to break said toggle connections between 60 the valve-actuating levers, a longitudinally movable member, a projection therefor adapted to be disposed in the path of the float, a pawl upon said member adapted to 65 actuate said bar longitudinally, disks upon
- said bar adapted to be engaged by said pawl, 65 means for tilting said member to release the pawl as the float approaches its highest limit.
9. A liquid dispensing apparatus comprising a tank with an inlet and an outlet 70 opening, valves regulating said openings, a spring-pressed, pivotal lever with connections between the same and said valves for causing the exit valve to open as the inlet closes, toggle link connections with the 75 lever for holding the same in adjusted position, a float and means actuated thereby for breaking said toggle link connections to allow the lever to return to its normal position, thereby causing the exit valve to 80 close as the inlet valve opens.
10. A liquid dispensing apparatus comprising a tank with an inlet and an outlet opening, valves regulating said openings, a spring-pressed, pivotal lever with connections between the same and said valves for causing the exit valve to open as the inlet 85 closes, toggle link connections with the lever for holding the same at its limit in one direction, a float and float-actuated means 90 connected to the toggle link connections for breaking the latter to allow the lever to return by spring action to its normal position.
11. A liquid dispensing apparatus comprising a tank with an inlet and an exit 95 opening, valves regulating said openings, a pivotal, spring-pressed lever connected to the stem of the outlet opening, means for tilting the lever, means for holding the lever in tilted position in one direction to cause the exit valve to remain open, a float and means actuated thereby for releasing the lever, a spring-pressed lever connected to the inlet valve, toggle link connections between 100 the levers, a longitudinally movable float-actuated bar, a lever pivoted thereto and having a lateral projection, pivotal link connections with the toggle links intermediate the levers, said link, which is pivotally connected to the lever having said projection, adapted to bear against the latter to cause the toggle link connections between 105 the levers to be broken.
12. A liquid dispensing apparatus comprising a tank with an inlet and an exit 115 opening, valves regulating said openings, a pivotal, spring-pressed lever connected to the stem of the outlet opening, means for tilting the lever, means for holding the lever in tilted position in one direction to cause the exit valve to remain open, a float and means actuated thereby for releasing the lever, a pivotal, spring-pressed lever connected to the inlet valve, toggle link connections between the levers, a longitudinally 120 movable, float-actuated bar, a lever pivoted thereto and having a lateral projection, pivotal link connections with the toggle 125

links intermediate the levers, said link, which is pivotally connected to the lever having said projection, adapted to bear against the latter to cause the toggle link 5 connections between the levers to be broken, and adjusting screws for regulating the toggle link connections.

In testimony whereof I hereunto affix my signature in presence of two witnesses.

JACOB EDWARD COFFEY.
